UNITED STATES PATENT OFFICE

GEORGE WILLIAM MURPHY, OF WANGARATTA, VICTORIA, AUSTRALIA

METHOD OF AND MEANS FOR ATTACHING THE UPRIGHTS AND MEMBERS OF SCAFFOLDING AND OTHER STRUCTURES

Application filed June 13, 1929, Serial No. 370,590, and in Australia August 22, 1928.

This invention has been devised to provide connected to an upright, the inner hooks of a gripping girt, hereinafter referred to, engaged in an upper recess of a bracket herein-after described.

5 In describing my invention, I shall refer to the use thereof with scaffolding employed in the erection and renovation of buildings, chimneys, and the like structures, and which consists of vertical uprights of any shape, 10 and transverse ledgers joined together and fastened by ropes and other devices at present in use, but it must be understood that this invention is not limited to scaffolding of the type referred to, as it may be employed 15 wherever it is desired to join two or more pieces of timber or other material firmly together especially for the purpose of supporting weight.

The objects of the invention are many, one 20 of which is to provide means comprising parts constructed of metal and which replaces the ordinary scaffold rope or cord at present so largely used and subject to failure, the result of decay and faulty binding or tying.

25 Another object of the invention is to provide a method of and means whereby the erection and dismantling of the scaffolding may be carried out in an expeditious and simple manner, and when the scaffold is erected will 30 provide a rigid structure for the purposes required.

As the means hereinafter described is simple in construction its manufacture is cheap, enabling sale to the public at a small cost; 35 furthermore the means employed permits of the erection of scaffolding material which can be used in the erection of a building and by doing so dispense with the present scaffolding poles, saving the cost of transport 40 thereon, and also saving the cost of maintenance thereof; thus on the timbers being dismantled from the scaffolding they will be undamaged and may be employed for the many purposes for which they were originally intended.

In order that my invention may be the more easily understood reference will be made to the accompanying drawing in which

50 Figure 1 is a perspective view of the preferred form of the clamp, and shows a ledger

55 Figure 2 is a view similar to that of Figure 1, the ledger being thicker and the inner hook of the gripping girt being engaged in the lower recess of the bracket. (The outer hooks or loops being similarly used when uprights of greater width are used.) 60

Figure 3 is a view similar to Figures 1 and 2 showing the clamp designed to accommodate an unusually thick ledger, or more than one ledger, or the lap joint of two ledgers, the inner hook of the gripping girt being shown 65 engaged to a lower recess of a bracket.

Figure 4 illustrates a bracket and girt set in position to loosely receive a ledger.

Figure 5 is a perspective view of a gripping girt with two hooks at each end. 70

Figure 6 is a perspective view of a gripping girt with one hook at each end.

Figure 7 is a perspective view of a gripping girt with end rings and integral lugs 75 thereon forming hooks.

Figure 8 is a perspective view of a gripping girt with rings and hooks.

Figures 9, 10 and 11 are perspective views, showing different forms of a U-shaped bracket.

Figure 12 is a perspective view, showing a single member bracket and a gripping girt connecting a ledger to an upright.

Figures 13, 14, 15 and 16 show in perspective modifications of the single gripping girt 85 illustrated in Figure 12.

Figures 17, 18 and 18a show in perspective different forms of a vertical bracket composed of one member whose lower end is bent to provide a shoe (or equivalent to the transverse member 5 of the U-shaped bracket).

Figure 19 is a section of the jaw portion of the gripping girt, and shows the preferred manner of forming teeth or serrations thereon.

Figure 20 is a side view of the clamp, and shows a ledger held to an upright by a gripping girt and U-shaped bracket, the latter having an eccentric lever engaging its jaw 100 portion.

Figure 21 is a similar view to Figure 20 with a wedge employed in lieu of the eccentric lever.

Figure 22 illustrates a chain useable as a gripping girt.

The preferred embodiment comprises a preferably U-shaped bracket 1, whose upper parallel portions 2 constitute jaw portions adapted to grip a ledger scaffold member 4. Said portions may have serrations, teeth or the like 3 (see Figure 10) to enhance the grip on the member 4. The lower transverse portion 5 of the U-shaped bracket constitutes a shoe bearing against one side of a supporting upright 6 of any desired configuration. The shape of the transverse portion or shoe 5 preferably corresponds with the shape of the upright surface with which it has sliding contact. The bracket is provided below the jaw portions 2 with step portions 9, adapted to support the ledger member 4, and with recesses 9a between the step portions, for a purpose hereinafter described.

Connected to the U-shaped bracket 1 below the jaw portions aforesaid is a gripping member 7 termed a girt or girt whose transverse portion 7a constitutes a girt, jaw bearing against the opposite side of the upright 6. Said jaw is provided with teeth 8 to enhance the grip on the upright 6 said teeth being preferably formed by displacing portions of the metal of the jaw in opposite directions so that the teeth are in different planes as shown by Figure 19. The teeth thus arranged enable the jaw to be inverted or arranged with either side uppermost so that the jaw is "fool proof", the teeth engaging the upright 6 equally well whether the jaw faces upward or downward. The said girt encircles the upright 6 at the rear of the U-shaped bracket 1 which may be shaped to provide any number of steps 9 whose shape furnishes a recess or recesses 9a so that quarterings or other timber of the desired size may be joined and the girt caused to effectively grip any particular shape of upright such as a pole to which it may be attached.

The girt 7 is approximately U-shaped and is provided with bracket engaging means such as hooks 11a (Figure 5) sliding on the bracket arms, the slideable movement of the girt in one direction being limited by the bracket shoe portion 5 as shown by Figure 4. Said bracket engaging means may be provided by loops or eyes 13 (Figures 7 and 8) the loops shown by Figure 7 being provided with lugs 14, so that the loops (or lugs) may function like the hooks 11a. Additional hooks 11, such as those shown by Figure 5, 60 may be provided to engage the bracket. Links shown by Figure 22 constituting members of a flexible chain length may be substituted for the rigid girts 7 or 70 and their jaws 7a or 70a, the end links 16 being adapted to receive the upper jaw portions 2 or 200

of the U-shaped brackets 1 or 100, respectively.

The object of the loops and hooks referred to at each end of the girt, or the large links at each end of the chain is to engage the desired recess 9a of the U-shaped bracket 1 and by doing so form a fulcrum so that when the bracket 1 slips down the upright 6 the ledger 4 is drawn into close contact therewith by means of the leverage exerted by its transverse portion 5 in sliding down and pressing against the upright 6. The bottom and transverse portion 5 of the bracket 1, according to its distance from the particular recess 9a in the bracket 1 and the hook 11, 11a or 14a, or loop 13 or link 16 of the chain 15, as the case may be, in the girt, increases the leverage and multiplies the pressure of the jaw portions 2 of the bracket 1, pressing the ledger tightly against the upright 6, and at the same time, when using a solid or inflexible girt 7, forcing the teeth 8 on the jaw 7a thereof into the opposite side of the upright 6, thereby ensuring a much firmer and more secure assemblage of the upright 6 and the ledger 4.

The bracket 1 may also be made single instead of U-shaped (see Figures 12, 17 and 18) and it may be stepped or recessed and furnished with a shoe portion 17 at its lower end which is wider than the bracket to bear against the upright 6 and by so doing exert the necessary leverage.

The single bracket shown by Figures 12, 17, 18 and 18a comprises a body portion 100 provided at one end with a shoe portion 17 which bears on the upright 6, and at the opposite end with a jaw portion 200 which bears on the ledger 4. The single bracket is also provided with one or more step portions 90 and one or more recesses 90a similar to the step portions 9 and recesses 9a on the U-shaped bracket.

The girt or girt used with the single bracket is shown by Figs. 13, 14, 15 and 16, and comprises a body portion 70, having at one end a jaw portion 70a, similar to the jaw 7a of the U-shaped girt. The opposite end of the body portion 70 is provided with means such as a hook 72 (Fig. 13), two hooks 72 (Fig. 14), a loop 73 (Fig. 15), or a loop 73 and a hook 72 (Fig. 16) for engaging the single bracket, as indicated by Figure 12, the girt shown in this figure having two hooks 72 (as in Fig. 14) either one of which may engage the single bracket. Fig. 15 shows the loop 73 provided with a lug 140 similar to the lugs 14 (Fig. 7).

Each form of bracket may have a plurality of steps 9 and recesses 9a to provide for a greater variety of ledgers. It is obvious that the bracket 1 may require a differently shaped girt with one hook or one loop, or one loop and one hook, or a multiple of hooks and loops to embrace a greater variety of

sizes of ledgers 4 and uprights 6, or if it is desired the chain girt (see Figure 22) may be used, said girt having a link near or at each end of the chain passed downwardly over the jaw portions 2 to the necessary position on the bracket 1. From the above it will be seen that the greater the weight or load within certain limits superimposed on the ledger, considering the strength of the component parts viz. the U-shaped bracket 1, the girt 7, the upright 6 and the ledger 4, the more securely will the apparatus grip and clamp the ledger against the upright.

The purposes of the invention are not limited to the use of scantlings or quarterings for the erection of scaffoldings, as by a slight alteration in the design of the means hereinbefore described it may be used for attaching round poles together similar to those employed in ordinary scaffolding and when designed for the use with ordinary scaffold poles may also be employed for attaching or joining square or other shaped timbers or scantlings of suitable size and dimensions.

When attaching the device for the purpose of erecting a scaffold, I first of all lay out the ledgers 4 along or around (as the case may be) the structure to be erected or demolished and approximately along the proposed line or position of the uprights 6, allowing each ledger 4 to lap for about one foot the next succeeding ledger if it is intended to erect a scaffold of any considerable length. I then set an upright 6 in the ground or in a cask, or may attach a base or foot to said upright 6 or adopt any other of the usual methods that will enable it to stand in position opposite each lap of the ledgers. Other uprights 6 are spaced and set in position at the desired distance between the uprights previously placed. I then take a girt 7 in one hand and a bracket 1 in the other, and first pass the girt around the upright 6 at the desired height. I then pass the bracket 1 upwards through the loops 13 or hooks 11, 11a, 14 or 14a or links 16 of the chain girt, according to the size of the ledger 4 and the size of the upright 6, until the bottom 5 of the bracket 1 prevents any further upward motion of the bracket 1, at the same time allowing the upper portion of same to fall outwardly away from the upright, then holding the girt against the back of the upright with one hand I remove the other hand from the bracket and the apparatus assumes the position shown in Figure 4. This, as will readily be seen, forms a temporary bracket and when this process has been repeated to each of the uprights 6 comprising that portion of the proposed scaffold, the workman may then lift and loosely place in the temporary brackets thus formed the ledgers 4 of the proposed scaffold.

It is obvious that a bracket of larger size will be required to accommodate the ledgers

where they lap (see Figures 3 or 11). Then the workman, standing under one end of the ledger 4, raises it slightly with his shoulder at the same time slipping the bracket 1 downwardly through the loop or loops or hook or hooks of the girt, until the said loop or loops, or hook or hooks, engage in the desired recess or recesses of the bracket 1 according to the size of the material being used, at the same time holding the ledger 4 in position for the portion or portions 2 of the bracket to engage the ledger 4. Then holding the girt 7 against the back of the upright 6 with one hand, the workman lowers his shoulder until the bracket 1 slips down the upright 6 engaging the ledger 4 and pressing it tightly against the upright 6. This operation is repeated until the ledgers are all assembled in their respective positions on the uprights. The intermediate clamps are similarly assembled, by finally sliding them up into their respective positions and firmly adjusting the gripping teeth of the girts.

The best adjustment for the girt is as near the horizontal as possible and for scaffolds of great height where it is necessary for the ledgers or uprights to be firmly fastened together although carrying no weight, a tensioning wedge 19 (Figure 21) of wood or other material may be driven upwardly between the jaw 5 of the bracket and the upright 6, until the girt is strained and adjusted into a horizontal position, when the wedge 19 may be secured to the upright with a nail 20a.

If desired an eccentric lever 20 (Fig. 20) with an open eye 21 sufficiently large to fit the jaw portion 5 of the bracket 1 may be employed and pressed downwardly forcing the girt 7 into a horizontal position and straining the ledger 4 to the upright 6. The eccentric lever 20 may also be a permanent attachment to the bracket i. e. with an eye sufficiently large to permit of free movement on the shoe portion 5, or it may be furnished with an eye sufficiently large to slip downwardly on the bracket to its position on said shoe portion 5 of the bracket. Sometimes a blow with a hammer or other suitable implement is availed of to tighten the bracket and ledger more securely in position.

It will be seen by the above method of operating the invention that a scaffold of any size (considering the weight of the component parts and the strength of the workman employed) may be erected by one man without assistance.

Another method that may be employed is to partly drive a nail in the back of each upright and immediately below the position of the girt, and after the scaffolding members and the device are all assembled together as aforementioned, to further drive the nail and bend it upwardly around the girt or the nail may be entirely withdrawn. In the case a short chain is used it will be necessary for the

workman to support the ledger on his shoulder or otherwise while the chain and the bracket are set in position and adjusted.

Various ways may be adopted for dismantling the scaffold. One is to forcibly drive the ledger upwards out of its position and another is to give the shoe portion 5 of the bracket 1 a sharp upward or ramming blow with a short piece of timber or other suitable implement, and hold the bracket momentarily (or in other words hit and hold) when the bracket will again assume the temporary position (see Figure 4) and loosely support the ledger 4 until it is convenient for the workman to remove the same. Where it is desired to remove the wedge 19 or the eccentric lever 20, it is advisable to withdraw the wedge or to release the eccentric lever before driving the bracket upwardly for the purpose of dismantling the scaffold. The device is then disassembled by reversing the actions for assembling.

It will now be seen that the bracket element of my improved clamp includes a shoe portion adapted to bear against one side of an upright member 6, a step portion 9, spaced above the shoe portion, and adapted to support a ledger member 4, recess portions 9a to receive engaging portions of a girt, and for purposes of adjustment to accommodate different sizes of ledger members 4, and a jaw portion 2 above the step portion, adapted to clamp the ledger member against the upright member, and a girt engageable with the bracket and including a jaw portion 7a adapted to bear against the opposite side of the upright member 6.

It will also be seen that the illustrated arrangement is such that the bracket and girt jaw portions are caused by the weight of the ledger member 4 to grip the opposite sides of the ledger 4 and upright 6, when the ledger member is supported by the step portion of the bracket, and that the clamp may be applied to the upright member 6, temporarily adjusted as shown by Figure 4 to loosely support the ledger member without exerting clamping pressure thereon, and then adjusted as shown by Figure 1 to cause the step and clamping portions to support and clamp the ledger member.

In the embodiment shown by Figures 12 to 18a inclusive the bracket is a single rod (not U-shaped) and has a one or two part step portion 9, one or more recess portions 9a, a one part jaw or clamping portion 2, and a shoe portion 17 projecting in opposite directions from the bracket, the shoe being wider than the bracket.

In the preferred embodiment shown by Figures 1 to 4, 9 and 11, and by Figures 20 and 21, the bracket is substantially U-shaped and has a duplex or two part step portion 9, 9 and a duplex jaw or clamping portion 2, 2.

The shoe portion 5 of the U-shaped bracket is a neck connecting the bracket arms.

I claim:

1. A scaffold clamp comprising a bracket including a shoe portion adapted to bear against one side of an upright scaffold member, a step portion spaced above the shoe portion and adapted to support a ledger member, and a clamping portion above the step portion adapted to exert clamping pressure on said ledger member; and a girt having means slidably engaged with said bracket, said girt including a jaw portion adapted to bear against the opposite side of the upright member and confine the bracket shoe portion thereagainst, the bracket shoe portion limiting the sliding movement of the girt on the bracket in one direction, the arrangement being such that the clamp may be applied to the upright member, temporarily adjusted to loosely support the ledger member without exerting clamping pressure thereon, and then adjusted to cause the step and clamping portions to support and clamp the ledger member, the step portion of the bracket being recessed to co-operate with the bracket engaging means of the girt in confining the clamping portion of the bracket against the ledger member when the latter is supported by the step portion. 95

2. A scaffold clamp comprising a bracket including a shoe portion adapted to bear against one side of an upright scaffold member, a step portion spaced from the shoe portion and adapted to support a ledger member, and a clamping portion above the step portion, adapted to clamp the ledger against the upright member; and a girt engageable with the bracket and including a jaw portion adapted to bear against the opposite side of the upright member, the arrangement being such that the weight of the ledger member and the load superimposed thereon exerted on the step portion, causes said jaw and shoe to grip said members and clamp the same together, the step and clamping portions of the bracket being duplex and provided by the arms of an approximately U-shaped body and the shoe portion provided by a neck connecting said arms at one end of the body, the girt being approximately U-shaped when in use and including end portions each having bracket engaging means slidably on said arms, said girt also having a neck portion having teeth arranged in different planes so that the girt is invertible. 110

In testimony whereof I have affixed my signature to this specification.

GEORGE WILLIAM MURPHY.
